United States Patent Office.

GEORGE NIMMO, OF JERSEY CITY, NEW JERSEY.

Letters Patent No. 64,352, dated April 30, 1867.

IMPROVEMENT IN THE MANUFACTURE OF FIRE-BRICK.

The Schedule referred to in these Letters Patent and making part of the same.

TO ALL WHOM IT MAY CONCERN:

Be it known that I, GEORGE NIMMO, of Jersey City, in the county of Hudson, and State of New Jersey, have invented, made, and applied to use a certain new and useful improvement in Composition for Fire-Brick, Furnace-Linings, Pots, Retorts, &c.; and I do hereby declare the following to be a full, clear, and exact description of the said invention, and of the features which distinguish the same from the compounds heretofore employed.

In the manufacture of fire-brick it has been usual heretofore to employ a peculiar quality of clay known as fire-clay, because it is of a consistence and quality adapting it to withstand high degrees of heat. These bricks are very often rapidly destroyed by the heat of steel and other furnaces. In the consumption of fuel the earthy portions that remain in the form of ashes, clinker, or cinder, have been exposed to a higher degree of heat than the linings of the furnaces in which such fuel is consumed, hence the combustible portions of the fuel are consumed, and the residuum is of a character adapted to withstanding almost any degree of heat without rapid change or destruction.

The nature of my invention or discovery therefore consists in the employment of the ashes or other residuum of the combustion of coal as the basis for the manufacture of fire-bricks, furnace-linings, pots, &c., said material being of a character the best adapted to withstanding an intense heat. In order to employ this material I mix therewith a sufficient quantity of clay, or of clay and fine sand, to cause the particles of ashes or other coal residuum to adhere together, and I mould the same into the desired shape. It will be understood that the more intense the fire is from which the residuum is taken the better the composition will be for withstanding high temperatures, and, according to the condition of that residuum, so the same may be made use of without sifting, or it may require to be ground as well as sifted previous to mixing with the clay.

What I claim, and desire to secure by Letters Patent, is—

The employment of the residuum of the combustion of coal as the base or principal component in the manufacture of fire-bricks, retorts, furnace-linings, pots, and similar articles, as and for the purposes specified.

In witness whereof I have hereunto set my signature this 5th day of February, A. D. 1867.

GEORGE NIMMO.
